(57) **CLAIM**

The ornamental design for an angled razor with side ports, as shown and described.

DESCRIPTION

FIG. 1 is an isometric view of an angled razor with side ports in accordance with the present application.

FIG. 2 is a back view of the angled razor with side ports.

FIG. 3 is a front view of the angled razor with side ports.

FIG. 4 is a first side view of the angled razor with side ports. FIG. 5 is a second side view of the angled razor with side ports.

FIG. 6 is a top view of the angled razor with side ports; and, FIG. 7 is a bottom view of the angled razor with side ports. The broken lines illustrate portions of the angled razor with side ports and form no part of the claimed design.
